(57) **CLAIM**

The ornamental design for a geometric ice form system, as shown and described.

DESCRIPTION

FIG. 1 is a side elevational view thereof;

FIG. 2 is a top plan view thereof;

FIG. 3 is a bottom plan view thereof;

FIG. 4 is an end view thereof;

FIG. 5 is an opposite end view thereof;

FIG. 6 is a perspective view thereof;

FIG. 7 is an exploded perspective view thereof;

FIG. 8 is a perspective view thereof;

FIG. 9 is a perspective view thereof; and,

FIG. 10 is a perspective view thereof.
